UNITED STATES PATENT OFFICE.

JOHANN PETER KORSCHILGEN, OF BERGISCH-GLADBACH, GERMANY.

RAG-ENGINE.

SPECIFICATION forming part of Letters Patent No. 268,806, dated December 12, 1882.

Application filed August 23, 1882. (No model.) Patented in Germany November 27, 1881. No. 18,875.

To all whom it may concern:

Be it known that I, the undersigned, JOHANN PETER KORSCHILGEN, of Bergisch-Gladbach, in Rhenish Prussia, Germany, have invented a new and useful Improvement in Rag-Engines, (for which I have obtained a patent in Germany, bearing date November 27, A. D. 1881, No. 18,875,) of which the following is a specification.

10 My invention has for its object to increase the efficiency of rag or washing engines used in paper-mills, and to reduce or avoid their destructive action on the fiber of weaker materials. It is illustrated by the annexed drawings, of which—

Figure 1 is a vertical section of an ordinary rag-engine, while Fig. 2 is a vertical section, and Fig. 3 is a plan view, of a rag-engine embodying my invention.

20 In the ordinary rag-engine the jaw B of the engine-bed is only composed of from six to eight vertical knives, on which the cylinder A

rests with its whole weight, while in my improved engine the jaw C surrounds a portion of the cylinder, varying from one-tenth to one-third of its circumference, and the knives or ribs composing it are placed radially to the cylinder, which is mounted in its bearings at such a height as to avoid a direct contact of its teeth with the jaw, or to obtain only a slight brushing contact.

What I claim is—

A rag-engine jaw of metal or stone and provided with radial knives surrounding from one-tenth to one-third of the circumference of the engine-cylinder, substantially as described and illustrated.

In testimony whereof I have signed this specification in the presence of two subscribing witnesses.

JOHANN PETER KORSCHILGEN.
